UNITED STATES PATENT OFFICE

160,735

JEWELRY CHARM OR THE LIKE

Louis Pollock, Dothan, Ala.

Application May 12, 1950, Serial No. 9,890

Term of patent 14 years

(Cl. D45—17)

To all whom it may concern:

Be it known that I, Louis Pollock, a citizen of the United Kingdom of Great Britain, residing at Dothan, in the county of Houston, State of Alabama, in the United States of America, have invented a new, original, and ornamental Design for Jewelry Charm or the like, of which the following is a specification, reference being had to the accompanying drawing, forming part thereof, in which:

Fig. 1 is a side elevational view of the charm or the like, showing my new design,

Fig. 2 is a front elevational view,

Fig. 3 is a top plan view thereof,

Fig. 4 is the opposite side elevational view of Fig. 1.

I claim:

The ornamental design for a jewelry charm or the like, as shown.

LOUIS POLLOCK.
